US00D422588S

United States Patent

[19]

Hunt

[11] Patent Number: Des. 422,588

[45] Date of Patent: ** Apr. 11, 2000

[54] **BODY SHAPE OF A COMMUNICATION DEVICE WITH FOLDABLE ANTENNA**

[75] Inventor: **Charles Curtiss Hunt**, Raleigh, N.C.

[73] Assignee: **Ericsson Inc.**, Research Triangle Park, N.C.

[**] Term: **14 Years**

[21] Appl. No.: **29/104,964**

[22] Filed: **May 14, 1999**

[51] LOC (6) Cl. **14-03**

[52] U.S. Cl. **D14/138**; D14/248

[58] **Field of Search** D14/137, 218, D14/138, 144, 147-148, 247-249, 140-142, 250, 240, 100, 115; 343/702; 379/433, 434, 419, 420, 428, 440, 368; 455/550-575, 90; D13/168; D18/2, 7

[57] CLAIM

The ornamental design for a body shape of a communication device with a foldable antenna, as shown and described.

DESCRIPTION

FIG. 1 is a front view of a communication device with a foldable antenna showing my design;

FIG. 2 is a back view thereof;

FIG. 3 is a side view thereof;

FIG. 4 is an opposite side view thereof;

FIG. 5 is a top view thereof;

FIG. 6 is a bottom view thereof;

FIG. 7 shows a front perspective view of the communication device of my design; and,

FIG. 8 shows a back perspective view of the communication device of my design with the foldable antenna in a extended position.

The broken lines shown herein are for illustrative purposes only and form no part of the claimed design.

It is certified that error appears in the above-identified patent and that said Letters Patent is hereby corrected as shown below:

Title page,

Showing the illustrative figure, should be deleted to appear as per the attached title page.

Drawings,

The Drawing Sheets, consisting of Figs. 1-7 should be deleted to be replaced with the drawing sheets consisting of Figs. 1-8, as per attached pages.

Signed and Sealed this

Sixteenth Day of July, 2002

Attest:

Attesting Officer

JAMES E. ROGAN
Director of the United States Patent and Trademark Office
